UNITED STATES PATENT OFFICE.

MYRON J. FERREN, OF WASHINGTON, DISTRICT OF COLUMBIA.

BREAD-CUTTING MACHINE.

1,032,055.

Specification of Letters Patent.

Patented July 9, 1912.

Application filed April 13, 1911. Serial No. 620,836.

To all whom it may concern:

Be it known that I, MYRON J. FERREN, a citizen of the United States of America, residing at Washington, in the District of Columbia, have invented certain new and useful Improvements in Bread - Cutting Machines, of which the following is a specification, reference being had therein to the accompanying drawing.

- 16 This invention relates to new and useful improvements in machines for slicing bread, and more particularly to the type shown in my patent issued November 23, 1909, and numbered 941,065, wherein means is provided for simultaneously cutting a loaf into a plurality of pieces at a single operation whereby the loaf is reduced into slices of the desired thickness more expeditiously than can be done by cutting each slice separately.
- 20 The primary object of the invention is to construct a machine of the type mentioned which will be extremely simple in construction, efficient in operation, and durable and satisfactory in use.
- 25 A further object is to provide a machine which can be operated by a single operating device to move the loaf to the cutters and operate the latter to perform the cutting operation.
- 30 A further object is to provide cutting means of improved construction which will cut a plurality of slices at a single operation cleanly and evenly, without tearing or crumbling the bread.
- 35 Still a further object is to provide a cutting mechanism which will permit of the ready adjustment of said mechanism to cut slices of varying thickness.
- 40 Another and important object is to provide intermittently operated feeding means for moving the loaf to the cutters, in combination with oscillating or draw cut knives or cutters, which are operated to perform their work, after each intermittent movement of
- 45 the feeding means.

To the ends above stated, the invention consists in the improved arrangement and combination of parts to be more fully hereinafter described, and the novelty of which will be particularly pointed out in the appended claims.

The invention is fully and clearly illustrated in the accompanying drawings, wherein:—

- 55 Figure 1, is a side elevation of the machine embodying my invention, Fig. 2, is an

end elevation thereof, Fig. 3, is a longitudinal section on the line 3—3 of Fig. 4, and Fig. 4, is a top plan view of the machine.

Referring to the drawings, 1 denotes a table or bed which is substantially rectangular in plan and of such material and dimensions as best suited for the purposes intended, said bed being preferably made of metal and being supported by the metal side frames 2, 2, 60 to which said bed is bolted or otherwise secured along its longitudinal edges. Within the side frames 2, 2 at a point adjacent one end of the same, are journaled the ends of a transversely extending rock - shaft 3, to 65 which are fixedly secured arms 4, 4. A second rock-shaft 5 is journaled in the side frames 2, 2 directly above the shaft 3, and to this rock-shaft 5 are also fixedly secured the arms 6, 6, which are similar in all respects to the arms 4, 4. The arms 4, 4 and 6, 6 extend from the rock-shafts 3 and 5 respectively, at right angles thereto and are preferably arranged to project in substantially the same direction. Furthermore, the 70 arms of each rock - shaft are preferably mounted thereon one at each end of the same, and carried by and extending between each pair of arms 4, 4 and 6, 6, is a transversely extending rod 7, said rods having 75 round journals on their ends, as shown at 7, where they are connected to the arms 4, 4 and 6, 6. These rods 7, 7 are preferably made angular in cross-section, being shown in the drawings as square, and are adapted 80 to serve as the supports for the knife blades or cutters 8, which are provided with openings 9 at each end thereof through which the rods 7, 7 pass, said openings being formed to correspond to the cross - section of the 85 rods. By the mechanism just described, the blades or cutters will, as the shaft or shafts are rocked, be given an intermittent forward and downward movement, or in broader terms, an oscillatory movement, for performing their cutting operation.

It is to be understood that the blades or cutters 8 are so mounted on the rods 7 as to be capable of being moved longitudinally of said rods; furthermore, that the number of 90 blades mounted on these rods will be varied according to the number of slices into which it is desired to cut a loaf, and means will be presently described for maintaining these blades in proper spaced relation for cutting 95 slices of determined thickness.

Suitably mounted upon the upper face

of the bed 1, is a sliding pusher or carriage 10, which is adapted to move the loaf to the cutters with an intermittent feed by mechanism to be presently described. Piv-
 5 otally secured to this carriage are a plurality of members or fingers 11, which at all times project between the cutting blades during the reciprocations of the carriage, one passing between each two blades. It will thus
 10 be seen that these members or fingers 11, serve as spacing means to hold the blades in the desired spaced relation during both the forward and backward movements of the carriage. The movements of the carriage
 15 may be guided by means of guide plates 12, one on each side of the said carriage, said guide plates extending upward from the bed 1, and bolted or otherwise secured to the side frames 2, 2, flanges 13 being provided on
 20 said guide plates which overhang the upper longitudinal edges of the carriage.

The spacing fingers 11, are all detachably secured by means of screws 14, to a trans-
 25 verse member 15, which is pivotally mount-
 ed on the carriage, and springs 16 are pro-
 vided for pressing the forward ends of the
 30 fingers in a downward direction, so that
 said fingers bear with yielding pressure
 upon the loaf during the feeding of said
 35 loaf to the cutters. Upon the rear end of
 each finger is formed a cam 17, which cams
 are adapted to coöperate at the proper time
 with a transversely arranged roller 18 jour-
 40 naled in the side frames 2, 2, and the pur-
 pose of such arrangement being to provide
 means for lifting or raising the forward ends
 of the fingers upon the return stroke of the
 45 carriage, such lifting of the fingers facilit-
 ating the placing of a loaf within the ma-
 chine. It will thus be seen that upon the
 50 return of the carriage from the cutters or
 blades, the finger cams 17 engage beneath
 the roller 18, and owing to the fact that the
 fingers are pivoted intermediate their ends,
 55 the forward ends of said fingers will be
 lifted for the purposes as above stated.

It is obvious from the above description
 that the cutting blades are free to move
 60 lengthwise of the shafts 3 and 5, and that
 they are spaced in proper relation by means
 of the fingers 11 carried by the feed car-
 riage, the distance between adjacent blades
 65 depending on the width of the fingers. In
 order to cut slices of different size, it is only
 necessary to change the carriage for one hav-
 ing narrower or wider fingers. In some
 70 instances it might be inadvisable to change
 the entire carriage and if this is so the fin-
 gers themselves may be detached from its
 75 carriage and replaced by another set, the
 transversely arranged member 15 being
 made removable for this purpose. With
 further reference to these spacing fingers 11,
 80 it is to be noted that they are curved upon
 85 their under side to more nearly conform to

the shape of the loaf and to securely hold
 said loaf in proper position beneath them.

Any preferred means may be provided for
 operating the rock-shafts 3 and 5, and inter-
 mittently moving the carriage, but I have 70
 devised and employed the following means
 as supplying an efficient mechanism for the
 purpose stated:—A power-shaft 19 is trans-
 versely arranged and journaled in the side
 frames 2, 2, and a sprocket wheel 20 is mount-
 ed on one end thereof, said sprocket wheel
 75 adapted to transmit motion to a smaller
 sprocket wheel 21 through the medium of a
 sprocket chain 22. The sprocket wheel 21
 is mounted on a stud shaft 23, and is pro-
 80 vided with an eccentrically arranged pin 24
 which is adapted to engage within a slot 25
 formed within an arm 26 which is fixedly
 mounted on the rock-shaft 3. It will thus
 be understood that as the sprocket wheel 21 85
 is rotated, the shaft 3 will be rocked, and
 the cutter blades given a forward and down-
 ward or oscillatory movement to perform
 their work in the slicing of a loaf. Also
 mounted upon the power-shaft 19 is a small 90
 sprocket wheel 27, and a sprocket chain 28
 connects the same with a somewhat larger
 sprocket wheel 29 for driving it. The
 sprocket wheel 29 is loosely mounted on a
 95 stud-shaft 30, and has fixed to one face there-
 of a wheel 31 having formed therein a cam
 slot 32. An arm 33 is pivotally mounted
 upon the transversely arranged shaft 34,
 which is located above the wheel 31, and this
 100 arm 33 is adjustably connected to a rod 35,
 which is detachably secured at its other end
 to the carriage. The arm 33 intermediate
 its ends has a pin or roller 36 projecting
 therefrom, which pin or roller is adapted to
 105 travel within the cam slot 32 when the ma-
 chine is in operation. The arrangement is
 such that power being applied to the shaft
 19, to rotate the sprocket wheel 29, the cam
 wheel 31 will be rotated, and by means of
 110 the pin and slot arrangement, the arm 33
 will be oscillated to reciprocate the carriage.
 In this connection it is to be understood that
 the cam slot for a portion of its length is
 arranged in stepped form as shown at *a*,
 115 with a dwell between each step, thus giving
 to the arm, and likewise the carriage which
 is connected to it, an intermittent movement
 in a forward direction or a direction toward
 the cutters. During the time of each dwell
 120 of the carriage in its intermittent movement
 toward the cutters, said cutters, by their op-
 erating mechanism, are given an oscillating
 movement to cut the loaf. Another portion
 125 of the cam slot, namely that indicated at *b*,
 is adapted to give the arm and likewise the
 carriage a quick return movement or a move-
 ment in a backward direction away from
 the cutters, and still another portion of the
 130 slot, and that indicated at *c*, is arranged
 concentric with the shaft upon which the

cam wheel is mounted, and when the pin is in this portion of the slot the carriage will be momentarily held at rest, and for a period long enough for a loaf to be inserted 5 within the machine.

From the mechanism just described for moving the cutters, and reciprocating the carriage, it will be understood that the loaf is fed forward a short distance, then held 10 momentarily at rest for a short period until the cutters have been oscillated to cut a portion of the loaf, when the loaf is again moved forward another short distance, so that when the cutters are again operated they 15 will cut still another portion of said loaf. In other words, the carriage and cutters are alternately operated in the performance of the work necessary for the cutting of the loaf. In order that the machine may be 20 driven manually if desired or occasion demands, I may provide one end of the shaft 19 with a hand crank 37, as shown in Fig. 1 of the drawing. The loaf is to be inserted within the machine at a point indicated at 25 38, and extending from the bed of the machine is a shelf 39, upon which the loaf may be supported prior to its insertion within the machine. A shelf 40 arranged at the 30 end of the machine where the cutters are mounted, may be provided for receiving and supporting the slices as they pass from the cutters.

Having thus described my invention, what I claim is:—

35 1. In a machine of the character described, the combination of a plurality of cutters, and intermittent feed mechanism having means for maintaining the cutters in spaced relation.

40 2. In a machine of the character described, the combination of a plurality of cutters capable of independent lateral movement, and intermittent feed mechanism having means for maintaining the cutters in 45 spaced relation.

3. In a machine of the character described, the combination of a plurality of oscillating cutters, and mechanism intermittently operated for feeding material to said 50 cutters.

4. In a machine of the character described, the combination of a plurality of oscillating cutters capable also of independent lateral movement, and feed mechanism 55 having means for maintaining the cutters in spaced relation.

5. In a machine of the character described, the combination of a plurality of oscillating cutters capable also of independent lateral movement, and intermittent feed mechanism having means for maintaining the cutters in spaced relation.

6. In a machine of the character described, the combination of an oscillating 65 support, a plurality of cutters mounted

thereon to oscillate therewith, but capable of free movement lengthwise of said support, and feed mechanism having means for maintaining the cutters in spaced relation.

7. In a machine of the character de- 70 scribed, the combination of an oscillating support, a plurality of cutters mounted thereon to oscillate therewith, but capable of free movement lengthwise of said support, and intermittent feed mechanism having 75 means for maintaining the cutters in spaced relation.

8. In a machine of the character de- 80 scribed, the combination of a plurality of cutters capable of independent lateral move- 85 ment, and pivotally mounted spacing fingers projecting between the cutters to maintain them in spaced relation.

9. In a machine of the character de- 90 scribed, the combination of a plurality of 85 cutters capable of independent lateral move- 95 ment, a reciprocating feed carriage, and spacing fingers pivotally mounted on said carriage and projecting between the cutters to maintain them in spaced relation.

10. In a machine of the character de- 90 scribed, the combination of a plurality of 100 cutters capable of independent lateral move- 95 ment, and pivotally mounted spring-pressed spacing fingers projecting between the cut- 105 ters to maintain them in spaced relation.

11. In a machine of the character de- 100 scribed, the combination of a plurality of 105 cutters capable of independent lateral move- 110 ment, and pivotally mounted spacing de- 115 vices for maintaining the cutters in spaced relation.

12. In a machine of the character de- 110 scribed, the combination of an oscillating 115 support, a plurality of cutters mounted thereon to oscillate therewith but capable of free movement lengthwise of the shaft, a reciprocating feed carriage having fingers projecting between the cutters to maintain them in spaced relation, and gearing oper- 120 ated from a single power shaft for oscillat- 125 ing said cutters and intermittently moving the carriage toward the cutters.

13. In a machine of the character de- 115 scribed, a plurality of oscillating cutters, a reciprocating feed carriage, means for inter- 120 mittently moving said carriage toward the cutters, and means for oscillating the cutters after each intermittent operation of the carriage.

14. In a machine of the character de- 120 scribed, a plurality of cutters, a feed mecha- 125 nism associated therewith, means for inter- 130 mittently moving said feed mechanism, and means for operating the cutters after each intermittent movement of the carriage.

15. In a machine of the character de- 130 scribed, a plurality of cutters, a reciprocating feed carriage, means for intermittently mov- 135 ing the carriage toward the cutters and also

- giving to the same a quick return movement, and means for operating the cutters to perform their work after each intermittent operation of the carriage.
- 5 16. In a machine of the character described, a plurality of cutters, a reciprocating feed carriage, means for intermittently moving the carriage toward the cutters and also for returning the same to normal position, and means for operating the cutters to perform their work after each intermittent operation of the carriage.
- 10 17. In a machine of the character described, a plurality of cutters, a reciprocating feed carriage, a stepped cam for intermittently moving the carriage toward the cutters, and means for operating the cutters to perform their work after each intermittent operation of the carriage.
- 15 18. In a machine of the character described, a plurality of cutters capable of independent lateral movement, a reciprocating feed carriage, and spacing fingers mounted on said carriage and having downwardly curved ends, said fingers projecting between the cutters to maintain them at all times in spaced relation.
- 20 19. In a machine of the character described, a plurality of cutters capable of independent lateral movement, a reciprocating feed carriage and spacing fingers mounted on said carriage having means for retaining the material being fed in proper relation to the feed carriage, said fingers projecting between the cutters to maintain them at all times in spaced relation.
- 25 20. In a machine of the character described, the combination of a plurality of cutters, a reciprocating feed carriage associated therewith, spacing fingers pivotally mounted on said carriage and projecting between the cutters to maintain them in spaced relation, and means carried by the fingers for co-operating with a part of the machine for lifting the forward end of said fingers at each reciprocation of said carriage.
- 30 21. In a machine of the character described, the combination of a plurality of cutters, a reciprocating feed carriage, means for intermittently moving the carriage toward the cutters, and means for operating the cutters to
- ward the cutters, spacing fingers pivotally mounted on said carriage and projecting between the cutters to maintain them in spaced relation, and means for lifting the fingers at the end of the backward stroke of said carriage. 55
22. In a machine of the character described, the combination of a plurality of cutters, a reciprocating feed carriage, means for intermittently moving the carriage toward the cutters, spacing fingers pivotally mounted on said carriage and projecting between the cutters to maintain them in spaced relation, a roller transversely arranged with respect to the fingers, and a cam mounted on the rear end of each finger and adapted to engage said roller for lifting the forward end of the fingers upon the backward stroke of the carriage or the movement of the carriage away from the cutters. 60
23. In a machine of the character described, the combination of a plurality of cutters, a reciprocating feed carriage, spacing fingers pivotally mounted on said carriage and projecting between the cutters to maintain them in spaced relation, a member transversely arranged with respect to the fingers, and means carried by the rear end of each finger and adapted to engage said transverse member for lifting the forward end of the fingers upon the backward stroke of the carriage. 65
24. In a machine of the character described, a plurality of cutters, a reciprocating feed carriage, a lever arm pivotally mounted upon the machine frame and connected to said carriage, a stepped cam also carried by the machine frame, a roller carried by the lever arm and adapted to co-operate with said stepped cam for intermittently moving the carriage toward the cutters, and means for operating the cutters to perform their work after each intermittent operation of the carriage. 70
